UNITED STATES PATENT OFFICE.

EMILY A. CORLISS, OF PROVIDENCE, RHODE ISLAND, ADMINISTRATRIX OF
GEORGE H. CORLISS, DECEASED.

MACHINE FOR FINISHING THE ENDS OF VALVE-BOXES OF STEAM-ENGINE CYLINDERS.

SPECIFICATION forming part of Letters Patent No. 450,400, dated April 14, 1891.

Application filed December 19, 1889. Renewed November 6, 1890. Serial No. 370,451. (No model.)

To all whom it may concern:

Be it known that GEORGE H. CORLISS, deceased, late a citizen of the United States, resident in the city and county of Providence, 5 in the State of Rhode Island, (represented by EMILY A. CORLISS, administratrix,) invented a new and useful Machine for Finishing the Ends of Valve-Boxes of Steam-Engine Cylinders, of which the following is a specification.

10 Prior to his invention, hereinafter described, Mr. CORLISS had, in finishing the ends of the valve-boxes of the cylinders of steam-engines to receive the bonnets, faced the valve-box ends by planing them upon the ordinary planing-machine, and had then moved the cylinder to the drilling-machine and drilled the bolt-holes, which were subsequently tapped by hand in the ordinary way. He had not counterbored the valve-boxes, but 15 had finished the end faces so as to make a steam-tight joint with the bonnet, which he fitted and bolted thereon. He found that in such method of finishing the ends of the valve-boxes inaccuracies were liable to occur; 20 that it was desirable that the several valve-boxes be bored equidistant from the center of the wrist-lever support or bearing in order to secure an accurate relative movement of the valves, and, further, that each of the 25 valve-boxes be bored perfectly parallel with each of the others and at right angles to the center line of the cylinder.

The purpose of his present invention is to provide a machine which will finish the ends 30 of the several valve-boxes at a single setting and adjustment of the cylinder, and thereby avoid the inaccuracies liable to occur from the frequent settings and adjustments of the cylinder requisite in the prior method of 35 treating the valve-box ends, and which will also counterbore all the valve-boxes equidistant from the center of the wrist-lever support and exactly parallel with each other and at right angles to the center line of the cylinder, thereby affording means for centering 40 the bonnets of the valve-boxes, and also for accurately boring the valve-boxes on another machine invented by him, for which application of even date herewith for Letters Patent, 45 Serial No. 334,507, has been made. He has

therefore combined in a single machine means for centering the cylinder with absolute correctness, means for facing, counterboring, drilling, and tapping simultaneously both ends of a valve-box by tools arranged to act 55 alternately, and each driven by its appropriate operating mechanism, provision for rotating the cylinder on its centering-pivots, so as to bring the valve-boxes successively before the finishing-tools, and other means for 60 holding the cylinder stationary during the performance of the several operations necessary in the finishing of the ends of a valve-box.

Provision is made for the lateral and also 65 for the endwise movement of the centering means, and also for the endwise movement of those parts of the machine carrying the finishing-tools to accommodate cylinders of different sizes, and for the endwise feed of 70 the counterboring-tools. Other provision is made for the radial feed of the facing-tools, and still other provision for operating the drills and tapping-tools.

The centering means consist of two jigs or 75 trunnions arranged in line with each other and adapted to engage with suitable bushing the counterbores previously made in two oppositely-located side flanges in the cylinder. The cylinder is thus held on an axis at right 80 angles to its center line or longitudinal axis, and it is rotated or tilted on this shorter axis to bring the valve-boxes successively in line with the finishing-tools. Heads mounted upon axes parallel with the axes of the jigs 85 just described carry the facing, counterboring, drilling, and tapping tools. An upright post or standard located midway of the machine and movable for purposes of adjustment in a line at right angles to the axes of 90 the jigs and heads already referred to carries a vertically-adjustable saddle upon which one end of the cylinder rests, and to which it may be secured to hold the cylinder with the ends of the valve-box in the correct line for treatment. 95

In the accompanying drawings, Figure 1 is an elevation of the machine. Fig. 2 is a plan of same, showing a cylinder held therein, a portion of the cylinder being broken away 100

and the supports for the end of cylinder not yet in position. Fig. 3 is a sectional elevation on line $\alpha\alpha$ of Fig. 2.

Similar letters of reference indicate like parts where they occur in the drawings.

A A A represent the stationary bed of the machine.

A' A' are housings gibbed upon the bed and movable laterally thereon by means of feed-screws b' , actuated by hand-wheels b . Jigs or trunnions B B are mounted and have their bearings in the housings A' A' and are movable endwise by feed-screws b^3 , actuated by hand-wheels b^2 . Housings A² A², also gibbed upon the bed and movable longitudinally thereon at will by means of the feed-screws c' and hand-wheels c , or automatically by power applied to said feed-screws c' through bevel-gears connecting with an upper right driving-shaft F, have journaled in each of them a hollow shaft C', carrying a head C, equipped with tools for facing, counterboring, drilling, and tapping the ends of the valve-boxes, all arranged for alternate operation, and each provided with appropriate operating mechanism, all of which are more fully described in another application for Letters Patent filed December 18, 1889, No. 334,157, of even date herewith.

D represents a rest vertically adjustable upon the post or standard D', gibbed upon the bed A and serving to support one end of the cylinder at the proper height during the operation of finishing the ends of a valve-box. The post D' is located midway of the machine and movable upon the bed of the machine by means of the feed-screw d' and hand-wheel d in a line at right angles to the axial lines of the heads and jigs C C and B B. There are two heads C, arranged with their axes in the same line and each arranged for longitudinal movement with their connections along the bed of the machine at will by hand and also automatically by power. There are two jigs B, likewise arranged in line with each other and also with their axial line parallel with the axial line of the heads. These jigs are each provided with means for moving them endwise, and also with their connections are provided with means for moving them laterally toward or from the heads in lines parallel thereto.

I will now describe the practical operation of this invention. The cylinder side flanges having been upon another machine, also invented by the said GEORGE H. CORLISS and the subject of another application for Letters Patent filed December 18, 1889, Serial No. 334,158, counterbored at exact right angles to the center line of the cylinder, is now brought to this machine herein described, and the trunnions or jigs B B having been properly adjusted relatively to each other and to the heads C C, and the rest D having also been adjusted relatively to the heads and jigs and all to accommodate the particular sized cylinder about to be treated, said cyl-

inder is mounted in the machine with the jigs B B engaging the two opposite counterbored side flanges and with one end of the cylinder secured to the vertically-adjustable rest D, which is held at the proper height to bring both ends of one of the valve-boxes in the proper position between the heads C C. The heads are then by their respective adjusting means moved longitudinally to bring the finishing-tools in the proper positions to operate upon the valve-box ends. Said finishing-tools are then by their respective operating mechanisms operated successively and face, counterbore, drill, and tap the valve-box ends, both ends of the valve-box being operated upon simultaneously. When the ends of one valve-box have been finished, the cylinder is partially rotated upon the jigs B B as pivotal axes (the cylinder having been released from the rest D) to bring the ends of another valve-box into the proper position between the heads C C, when the end of the cylinder is secured to the rest D, held at the proper height, and both ends of this valve-box are finished. This is repeated until the ends of all four valve boxes have been faced, counterbored, drilled, and tapped, and the cylinder, in so far as the operations upon the ends of the valve-boxes are concerned, is finished ready for use. The wrist lever support is mounted and centered upon one of the side flanges engaged by the jigs B, and since in this machine the pivotal axis of the cylinder is at exact right angles to the center line of the cylinder, and as a uniform distance is maintained between such pivotal axis and the axes of the heads C C, it is obvious that the several valve-boxes will be counterbored equidistant from the center of the wrist-lever support, and at exact right angles to the center line of the cylinder and parallel with each other, and, furthermore, that since the pivotal axis of the cylinder and the axes of the heads C C are parallel with each other and at right angles to the center line of the cylinder the ends of all the valve-boxes will be faced parallel to said center line.

I claim as the invention of said GEORGE H. CORLISS and desire to secure by these Letters Patent—

1. A machine for finishing the ends of valve-boxes of steam-engine cylinders and for analogous purposes, consisting of the following elements in combination: first, jigs arranged with their axes in the same line and each capable of both endwise and lateral movement at will for purposes of adjustment, and by engaging the counterbore in two opposite side flanges of the cylinder adapted to serve together as a pivotal axis at right angles to the center line of the cylinder; second, two heads arranged with their axes in the same line and parallel to the axial line of the jigs, each equipped with tools for facing, counterboring, drilling, and tapping, and with means for operating each tool successively, and each head capable of longitudinal movement at

- will, and automatically, for purposes of adjustment and for feeding endwise such of the tools as require it, and also with provision for automatic radial feed of the facing-tool; third, 5 a vertically-adjustable rest also adjustable relatively to the axial lines of the heads and jigs, and in a line at right angles thereto, and serving as a support to hold one end of the cylinder at the proper height, as described.
- 10 2. In a machine for finishing the ends of valve-boxes of steam-engine cylinders and for analogous purposes, the jigs B B, housings A' A', and bed A, combined with each other, and with means, as the hand-wheel b b and traversing screws b' b', for moving the 15 housings and jigs laterally upon said bed for purposes of adjustment, and with means, as head C and tools operated therein, for treating the lateral faces of the casting held by
- 20 said jigs, all substantially as herein specified.
- 25 3. In a machine for finishing the ends of valve-boxes of steam-engine cylinders and for analogous purposes, a jig B and housing A', combined with each other and with means, as the hand-wheel b and feed-screw b', for moving the 25 housings and jigs laterally, and with means, as the hand-wheel b² and threaded shaft b³, for securing endwise movement of the 30 jig in the housing, so as to attain adjustment in both directions, and with tools operated by the heads C C for treating the faces of a casting held thereby, all substantially as herein specified.
- 35 In testimony whereof I have hereunto set my hand in the presence of two subscribing witnesses.
- EMILY A. CORLISS,
Administratrix of the estate of George H. Corliss, deceased.
